UNITED STATES PATENT OFFICE.

THOMAS WALLIS, TRAITON W. WALLIS, AND HARRY E. WALLIS, OF JANEVILLE, WISCONSIN.

CABINET BATH.

SPECIFICATION forming part of Letters Patent No. 379,143, dated March 6, 1888.

Application filed April 23, 1887. Serial No. 235,909. (No model.)

To all whom it may concern:

Be it known that we, THOMAS WALLIS, TRAITON W. WALLIS, and HARRY E. WALLIS, citizens of the United States, residing at Janesville, in the county of Rock and State of Wisconsin, have invented certain new and useful Improvements in Cabinet Baths; and we do declare the following to be a full, clear, and exact description of the invention, such as will 5 enable others skilled in the art to which it app pertains to make and use the same, reference being had to the accompanying drawings, and to the letters and figures of reference marked thereon, which form a part of this specification. 10

Our invention relates to improvements in cabinet baths; and it consists in the peculiar construction and arrangement of parts, as will 15 be hereinafter fully described, and pointed out in the claims.

The object of our invention is to provide a portable cabinet bath which will be a slightly, compact, and convenient piece of furniture, adapted for sleeping or other apartments, and 20 afford full facilities for a thorough bath, heat, and other necessary conveniences.

In the accompanying drawings, Figure 1 is a perspective view of the cabinet closed. Fig. 2 is a similar view showing the cabinet with 25 door open. Fig. 3 is a vertical section on line $x x$, Fig. 2.

The cabinet 1 is formed of wood set together in loose panels, having tongue-and-groove connection to allow for expansion and contraction 30 during the changes of temperature within the cabinet. Said cabinet is composed of the sides 2, front 3, back 4, and top 5. The cabinet is also divided into two compartments by the floors.

40 H M N is a semicircular opening in the top of the cabinet.

A is a reservoir, which is placed on the top of the cabinet, and is provided with a short screw-threaded discharge-pipe, a , which is 45 adapted to screw into one end of the spray-pipe B, as shown in Fig. 3. The pipe B, which is about one inch in diameter, is bent inside at right angles from its attachment to the reservoir, brought close to the front, and is then 50 bent around under the edge of the semicircular

opening N. The pipe B is perforated, as shown at $b b$, so as to distribute water thoroughly over the bather.

C represents a stop-cock located in the pipe B between the point of connection to the reservoir and the perforations. 55

D represents a shampooing-hose attached to the pipe B between the stop-cock and the reservoir. The hose D is provided with a stop-cock, o . 60

E represents an endless towel adapted to be secured to the cabinet at a point about in rear of the back of the bather. The towel E is flexibly secured to the cabinet by means of a spring-wire, e , which is so bent as to hold the 65 towel in the most convenient position, and is supported on the springs $f f$, secured to the top of the cabinet. Arranging the towel in the manner described renders it flexible, so as to rub the shoulders and back of the bather 70 where he could not reach them with his hands.

H represents the central or false floor, upon which the bather rests.

F represents a movable chair of ordinary construction. 75

I represents a lamp, which may be an oil, gas, or alcohol burner. This lamp is provided with a deflector to lead the heat into the main compartment by means of the pipe G. This pipe G is fitted water-tight through an aperture in the floor H, and is provided with a cap, g , or damper g' , to cover it and shut off the heat, when desired. The floor H, which is water-tight, is provided with an escape-pipe, L, which conveys the waste water into a receptacle, K, as shown in Fig. 3. The lamp I and waste-bucket K may readily be removed from the cabinet through a door in the lower portion of the cabinet. 85

The operation of our cabinet is as follows: 90 The bather, after taking his place in the cabinet, closes the door 6, his head protruding through the opening N. The cabinet may then be quickly heated to the required temperature by means of the lamp I, and when the desired 95 temperature has been reached the heat may be cut off by placing the cap g over the pipe G. The bather then turns on the stop-cock in the spray-pipe, and may thus give himself a shower-bath; or he may use the hose D by opening the 100

stop cock Q; or both hose D and pipe B may be used at the same time, if desired. After washing, the bather can rub his back on the towel E. The bather may be attended from 5 the outside of the cabinet without being exposed to the attendant.

The cabinet is provided with suitable castor-wheels, and also with an ornamental top piece, as shown in Fig. 1. In the inside it may have 10 one or more shelves, K, if desired.

By the above-described invention it will be seen we provide a neat and substantial cabinet 15 for a bath, which may be conveniently handled and, when not in use, represents a neat piece of furniture.

Having thus described our invention, what we claim is—

1. In a bathing-cabinet, the combination, with an upper and lower chamber, the former 20 having an aperture in its top, a water-tank located above the aperture and in close proximity thereto, a perforated spray-pipe leading from the tank around the aperture in the top of the cabinet, a flexible shampooing-pipe, also 25 leading from the tank, and a towel-holder suspended in close proximity to the aperture in

the top, of a heater located in the lower compartment, said heater provided with a pipe which passes through the floor of the upper chamber, the pipe having a cap or damper for 30 shutting off the heat, a drip-pipe in the floor of the upper chamber, and a tank beneath said pipe, substantially as set forth.

2. In a bathing-cabinet, the combination, with an upper and lower compartment, the upper compartment having an aperture in its top, of a water-tank located in close proximity to the said aperture, a spray-pipe leading from the tank around the aperture, a flexible shampooing-pipe, also leading from the tank, said 40 pipe being provided with a spraying-nozzle and a valve, and a towel-holder suspended in the upper compartment in close proximity to the spray-pipe, substantially as set forth.

In testimony whereof we affix our signatures 45 in presence of two witnesses.

THOMAS WALLIS.

TRAITON W. WALLIS.

HARRY E. WALLIS.
